ADJUSTABLE SHOWER HEAD

Robert W. Hyde, Crystal River, Fla., assignor to Pryde, Inc., Cincinnati, Ohio, a corporation of Ohio
Filed Apr. 1, 1964, Ser. No. 356,447
19 Claims. (Cl. 239—460)

This invention relates to shower heads and has to do more particularly with the construction of an improved shower head which is readily adjustable by the user to vary the flow of water therethrough.

While numerous expedients have hitherto been proposed for adjusting the flow of water through a shower head so that the user may selectively regulate the flow from sharp needle-like jets down to relatively large, low velocity streams, such adjustable heads for the most part are of relatively complex construction and hence too expensive for many installations wherein price is a controlling factor. Lesser expensive adjustable shower heads have also been proposed, but these in large measure rely on an adjustable button or similar deflecting member located at the outlet end of the head to diffuse the stream of water, it being necessary for the user to insert his hand into the path of the stream to make the adjustment. Usually this is done by turning the button which is threaded into the head or by turning a threaded member effective to displace the deflector toward or away from an outlet orifice in the head. Such arrangements are highly unsatisfactory in that the user's hand must be inserted into the path of the stream in order to make the necessary adjustment, the hand removed to observe the results, and then reinserted one or more times if further adjustment is required. Often times such movements result in water being sprayed into the user's face or elsewhere where not intended. In addition, the average water supply contains mineral matter and scale which collect on the shower head with the result that the threaded fittings readily clog and "freeze," and the devices are no longer adjustable.

The instant invention overcomes the aforementioned difficulties by providing a plastic shower head which is free from threaded connections between its relatively movable parts, adjustment being effected by rotating the entire nozzle portion of the shower head which may be readily gripped by the user from outside the path of the spray.

Accordingly, it is a principal object of the instant invention to provide an improved adjustable shower head of the character described wherein the shower head is composed of a plurality of interfitting parts which may be readily molded from plastic materials. Due to the lack of electrolytic action between plastic materials and water, mineral matter and scale are not held on the parts. Plastic materials are also relatively inexpensive and hence materially reduce the cost of the device.

A further object of the instant invention is the provision of a shower head composed of a plurality of parts which, when fitted together, are interlocking and maintain their assembled relationship without resort to bolts, setscrews or other threaded connections. At the same time the construction is such that the nozzle portion of the head may be rotated relative to the remaining parts thereof to effectively vary the flow of water therethrough.

A further object of the invention is the provision of a nozzle construction wherein the nozzle is provided with a centrally disposed outlet orifice opening into a cup-shaped spray chamber, with a button or deflector mounted so as to direct the stream of water flowing through the outlet orifice radially outwardly and downwardly through the spray chamber, the arrangement of parts being such that adjustment is effected by moving the nozzle part relative to the button deflector rather than by moving the deflector itself.

2

Still a further object of the instant invention is the provision of a shower head of the character described composed essentially of a swivel part, a core part, a nozzle part, and a button deflector, all of which are maintained in assembled relation by means of coacting sets of barbed fingers wholly contained within the assembled head, one such set of barbed fingers serving to operatively connect the nozzle part to the core part while at the same time mounting the parts for rotation relative to each other, the said parts including cam means operative upon such relative rotation to effect axial movement of the nozzle relative to the button deflector, thereby effectively adjusting the flow of water through the head.

Still another object of the instant invention is the provision of a shower head of the character described which is essentially tamper proof in that the locking fingers which secure the parts together are wholly enclosed within the assembled unit, although if it becomes necessary to remove the deflector for cleaning purposes, it may be disengaged by inserting a tool into the head through the swivel end thereof to release the barbed fingers which hold the deflector in assembled relation.

Yet another object of the instant invention is the provision of an adjustable shower head of the character described which is essentially self-cleaning in that the stream of water flowing through the head is converted into a spray by causing it to flow through a series of radially disposed grooves formed in the cup-shaped spray chamber, the grooves curving outwardly and downwardly from the centrally disposed outlet orifice in the nozzle with the flow of water serving to continuously flush and clear the grooves.

The foregoing together with other objects of the invention which will appear hereinafter or which will be apparent to the skilled worker in the art upon reading this specification, are accomplished by that construction and arrangement of parts of which an exemplary embodiment shall now be described.

Reference is now made to the accompanying drawings wherein:

FIGURE 1 is an exploded side elevational view with certain parts shown in sections and others in dotted lines illustrating an adjustable shower head constructed in accordance with the instant invention.

FIGURE 2 is a plan view of the underside of the swivel part of the shower head.

FIGURE 3 is a top plan view of the core part of the shower head.

FIGURE 4 is a bottom plan view of the core part.

FIGURE 5 is a bottom plan view of the nozzle part of the device.

FIGURE 6 is a top plan view of the nozzle part of the device.

FIGURE 7 is a side elevational view taken from the right hand side of FIGURE 6.

FIGURE 8 is a vertical cross-sectional view of the assembled shower head illustrating the nozzle part in one position of use, the view being taken along the line 7—7 of FIGURE 3.

FIGURE 9 is a vertical sectional view with parts broken away illustrating the nozzle part in another position of use, the view being taken along the line 8—8 of FIGURE 3.

For a general understanding of the invention, reference is first made to FIGURE 1 of the drawings wherein it will be seen that the unit comprises a swivel part 1, a core part 2, a nozzle part 3, and a button deflector 4. In addition, a ball coupling 5 is provided by means of which the shower head will be operatively connected to a water pipe (not shown) forming a part of the conventional plumbing necessary to establish a shower outlet.

The coupling is of conventional character, having an

attachment portion 6 which is normally threaded internally to receive mating threading on the end of the supply pipe, the coupling terminating at its opposite end in a ball portion 7 of generally spherical configuration. The coupling has an internal bore 8 through which water may flow, there being an outlet opening 9 at the lowermost end of the ball portion which will communicate with the interior of the shower head. As is well known, the ball coupling provides a convenient means for adjusting the position of the shower head, the coupling providing a universal joint by means of which the user may adjust the position of the shower head.

The head itself is operatively connected to the ball joint by means of the swivel part 1 which comprises essentially a tubular body portion or socket 10 terminating downwardly in an annular skirt portion 11. A pair of locking fingers 12 project downwardly from opposite sides of the skirt portion 11, the fingers 12 terminating at their lowermost ends in barbs 13 which, as will be pointed out in greater detail hereinafter, are adapted to enter into interlocking engagement with finger receiving slots in the core part 2. At its uppermost end, the tubular body portion 10 of the swivel terminates in an inturned annular lip 14, the internal diameter of which is somewhat smaller than the internal diameter of the body portion 10.

The swivel part will be molded from a plastic material, such as a thermoplastic resin characterized by high strength and stiffness combined with toughness and resiliency over a wide temperature range, together with good dimensional stability in the presence of moisture. Delrin, which is an acetal resin manufactured by the E. I. du Pont de Nemours & Co., is exemplary of thermoplastic resins having the desired characteristics. It will be understood, of course, that materials other than resins or plastics may be employed provided they are sufficiently resilient to permit flexing the locking fingers. Plastic materials are nonetheless preferred due to their lack of electrolytic action in the presence of water as well as their ability to be readily molded and also because of their relatively low cost. In addition, such materials possess excellent bearing characteristics—being lubric by nature—which is advantageous where the parts are in conduct and move relative to each other. Consequently, it is preferred that all of the parts of the shower head, namely, the swivel, the core, the nozzle, and the deflector be formed from plastic. In fact, the ball coupling 5 may be formed from plastic if so desired, although it is preferred that it be formed from metal in conventional fashion.

The dimensioning of the parts of the swivel will be such that the internal diameter of the tubular body portion 10 will be slightly smaller than the diameter of the ball 7; it being intended that the ball coupling be inserted into the swivel from beneath, with the inner surfaces of the tubular body portion 10 press fitted into gripping engagement with the mid-section of the ball 7, thereby providing a seal and at the same time permitting adjustment of the shower head. Since the annular lip 14 is of smaller diameter than the tubular body portion 10, it will prevent the swivel part from being disengaged from the ball coupling after the parts have been assembled. It also should be pointed out that the external diameter of the attachment portion 6 of the ball coupling 5 will be such that it may be readily passed upwardly through the annular lip 14 as the parts are assembled. Preferably, the internal diameter of the lip will be slightly greater than the external diameter of the attachment portion 6, thereby readily facilitating the assembly of the parts.

The core part 2 has a centrally disposed flow tube 16 the upper end of which is dimensioned to be press fitted within the tubular body portion or socket 10 of the swivel part, thereby providing a seal between the tubular body 10 and the flow tube 16. The uppermost end of the flow tube 16 will be chamfered at 17 so that, when

the flow tube is received within the tubular body portion of the swivel part, the chamfered surface will closely approach or even contact the ball 7 of the coupling 5. A jacket 18 surrounds the flow tube 16 and lies in spaced relation thereto, the jacket being connected to the flow tube by means of a spider-like member 19. This member is provided with an opposing pair of slots 20 of a size to receive the locking fingers 12 of the swivel part; and it is also provided with an opposing pair of elongated arcuate slots 21 which, as will be explained in greater detail hereinafter, are adapted to receive a pair of locking fingers forming a part of the nozzle 3. In addition, and as best seen in FIGURE 3, the upper surface of the core part 2 is provided with a pair of inclined cam tracks 22 lying immediately beyond the elongated arcuate slots 21, the cam tracks each having a lowermost end 22a and an elevated end 22b. As seen in FIGURE 4, the under surface of the spider-like member 19 is provided with a pair of cam tracks 23 lying immediately beyond the elongated arcuate slots 21, the cam tracks 23 having their lowermost ends at 23a and their uppermost ends at 23b. The orientation of the cam tracks 22 and 23 relative to each other is such that the raised or high ends 22b of the cam tracks 22 overlie the low ends 23a of the cam tracks 23. This arrangement, as will become apparent hereinafter, serves to effect axial movement of the nozzle part 3 relative to the core part 2 where the nozzle part is rotated.

The flow tube 16 of the core part has central portion 24—which may be slightly restricted if desired—in which a bar 25 is mounted, the bar being centrally disposed within the central portion of the flow tube and having a recessed portion 26 at its center. At the lowermost end of the central portion 24, the flow tube expands outwardly into a somewhat enlarged lower portion 27 having an annular shoulder 28.

The nozzle part 3 has a centrally disposed tubular neck portion 30 of a size to be received within the central portion 24 of the flow tube 16. The neck portion 30 terminates downwardly in an enlarged portion 31 which, at its juncture with the portion 30, defines an annular seat 32 for an O-ring 29. The O-ring is thus confined between the seat 32 and the annular shoulder 28. Alternatively, the neck portion may be sized to be lightly press fitted within the flow tube to the elimination of the O-ring. The enlarged neck portion 31 flares downwardly and outwardly at 33 to define a centrally disposed spray chamber 34, the spray chamber 34 curving downwardly and outwardly from a centrally disposed outlet orifice 35. Essentially, the nozzle part has a flat under surface 36 surrounding and projecting outwardly from the lowermost edge of the spray chamber 34; and the spray chamber itself is provided with a plurality of radially disposed vanes 37 which define flutes or grooves 38 through which the stream of water flowing through the outlet orifice 35 will be caused to flow, the flutes acting to convert the stream into a spray composed of a multiplicity of individual jets.

The nozzle part additionally includes an annular flange 39 projecting upwardly and outwardly from the flat under surface 36, the up-turned flange being provided with a plurality of spaced apart pods 40 by means of which the user may readily grip the nozzle part to rotate it. An opposing pair of spacers 41 project upwardly from the nozzle part and are positioned to be received within an annular recess 42 formed in the under surface of the spider-like member 19 of core part 2, with the flat bottom surface of the recess defining a pair of semi-circular cam tracks 42a and 42b separated from each other by the ledges 43a and 43b. Thus, the cam track 42a will have its low end at the ledge 43b—which is also the high end of cam track 42b—whereas the high end of cam track 42a and the low end of cam track 42b will be at the ledge 43a.

The nozzle part is also provided with an opposing pair of upwardly projecting locking fingers 44 which, as best seen in FIGURE 7, have outwardly directed barbs 45

positioned to engage the arcuate slots 21 in the core member 2 with the under surfaces of the barbs 45 seated on the cam tracks 22. The fingers also incorporate outwardly projecting ledges 46 which are adapted to underlie the spider-like member 19 with the ledges contacting the cam tracks 23 formed in the under surface of the spider-like member.

The button deflector 4 comprises a circular body 47 the diameter of which is greater than the diameter of the outlet orifice 35 in the nozzle but of a size to freely fit within the spray chamber 34 between the innermost edges of the vanes 37. The upper surface of the circular body 47 will be tapered or curved, as indicated at 48, so that when the button is associated with the nozzle, water flowing through the outlet orifice 35 will be deflected radially outwardly and downwardly into the flutes 38; and in this connection, it will be remembered that the spray chamber 34 is also curved outwardly and downwardly so that, as the stream of water passes through the outlet orifice 35, it will be immediately deflected in a radial yet downwardly curved path. Projecting upwardly from the circular body 47 is an opposing pair of gripping fingers 49 of a size to extend freely upwardly through the outlet orifice 35, the fingers having inturned barbs 50 on their uppermost ends adapted to engage the bar 25 in the core part with the barbs seated in recess 26. Preferably, the engagement of the bar 25 by the fingers 49 will be loose, that is, while the fingers will serve to secure the button part to the bar and hence to the core part, their connection will nonetheless be non-rigid so that there may be sufficient "play" in the button to permit it to be self-centering relative to the outlet orifice 35 in the nozzle part.

The assembled condition of the shower head is illustrated in FIGURES 8 and 9. As will be seen therein, the ball portion 7 of the coupling 5 is press fitted within the tubular body or socket 10 of the swivel part 1 with the annular lip 14 surrounding the surface of the ball above its mid-section. The press fit affords a water tight seal between the parts and yet the plastic swivel permits pivotal movement so that the position of the shower head may be adjusted. At the same time, the upper end of flow tube 16 is press fitted within the lowermost end of the tubular body portion 10 with the chamfered upper edge of the flow tube approaching or even contacting the surface of the ball immediately below its mid-section. This arrangement provides a water tight seal between the swivel part and the core part. Consequently, gasket means are not required between the ball coupling and the upper end of the flow tube. Of course, if desired, the upper end of the flow tube may be configured to receive a conventional gasket or washer adapted to seat against the ball without departing from the spirit and purpose of the invention.

As will be evident from FIGURE 8, the locking fingers 12 project downwardly through the slots 20 in the core part where their barbs 13 engage beneath the spider-like member 19, thereby locking the swivel part to the core part. Similarly, the locking fingers 44 of the nozzle part project upwardly through the slots 21 with the barbs 45 engaging the cam tracks 22. In addition, the ledges 46 on the barbs seat against the cam tracks 23 formed on the under surface of the spider-like member 19. The fingers 44 thus act to lock the nozzle part to the core part; and in so doing, the neck portion 30 of the nozzle will be received within the restricted central portion 32 of the flow tube 16, and the O-ring 29 will be confined between the neck portion 30 and the enlarged lower portion 27 of tubular member 16, thereby effecting a tight internal seal between the nozzle and the core part. The nozzle part is thus securely fastened to the core part and a water tight passageway effected between the outlet opening 9 in the ball joint and the outlet orifice 35 in the nozzle. At the same time, the nozzle part is mounted for rotation relative to the core part, the degree of rotation being determined by the length of the arcuate slots 21 through which the

locking fingers 44 extend. In this connection, it will be remembered that the barbs on the upper ends of the locking fingers contact the cam tracks 22, whereas the ledges on the fingers contact the cam tracks 23; and as already pointed out, the cam tracks 22 and 23 are so oriented with respect to each other that the lowermost ends 22a of the cam tracks 22 overlie the uppermost or high ends 23b of the cam tracks 23. In addition, the pitch of the cam tracks 22 and 23 will be the same, preferably on the order of two or three degrees, so that as the nozzle is rotated the barbs 45 will ride "up" the cam tracks 22 while the ledges 46 will ride "down" the cam tracks 23, and vice versa. This results in the nozzle part being moved toward and away from the core part depending upon the direction of rotation of the nozzle part. The opposite inclination of the cam tracks 22 and 23 relative to each other maintains the two parts in tight engagement at all times during their rotative movement. Further stabilization of the parts is obtained by means of the spacers 41 which project upwardly from the nozzle part and have the free ends seated on the cam tracks 42a and 42b. Upon rotation of the nozzle part, the spacers ride along the cam tracks 42a and 42b which have the same pitch as the cam tracks 22 and 23 and are oriented in the same direction as the cam tracks 23.

The button deflector 4 is mounted with its body part 47 underlying the outlet orifice 35 and its gripping fingers 49 projecting upwardly through the neck of the nozzle where the barbs 50 engage about the bar 25 of the core part, thereby effectively securing the deflector to the core part. While, as already pointed out, the deflector is loosely secured to the core part so that it will be self-centering, the button is nonetheless effectively anchored to the core part—which is a stationary part—and hence the longitudinal position of the deflector is maintained. Thus, when the nozzle part is rotated and hence moves axially relative to the core part, it will likewise move axially relative to the button deflector and in so moving the outlet orifice 35 will be moved toward and away from the deflector. The relative positions of the nozzle part and the deflector can be seen by comparing FIGURES 8 and 9. In FIGURE 8, the nozzle has been rotated so that it is axially displaced in the direction of the core part, with the result that the curved or tapered upper surface 48 of the deflector lies in spaced relation to the curved inner surface of the spray chamber 34. In this position the deflector will deflect a relatively wide sheet of water into the spray chamber resulting in a coarse spray. On the other hand, if the nozzle part is rotated so as to displace it axially outwardly, it will approach the body of the deflector, with the result that a relatively thin sheet of water will be deflected into the spray chamber at a higher velocity—due to the effectively smaller flow area—resulting in a fine spray. It should thus be apparent that depending upon the relative adjustment of the parts, the flow of water may be effectively regulated between a coarse and a fine spray, depending upon the wishes of the user. Yet the adjustment is a simple one in that the user has merely to grasp and turn the nozzle part, which will be readily accessible from outside the spray area, thereby permitting the user to observe the results of the adjustment while the adjustment is being made and also avoiding the unpleasant splashing which results where the user's hand must be inserted in the spray area in order to make the desired adjustment.

The external construction of the shower head is such that the several parts coact to provide a neat and attractive unit. Thus, the skirt portion 11 of the swivel part lies in close proximity to the upper edge of the jacket 18 of the core part, which jacket preferably will just nicely fit within the confines of the annular flange 39 of the nozzle. In order to enhance the appearance of the unit, it is contemplated that a cover member 51, as seen in FIGURE 9, may be slipped over the skirt 11 and the jacket 18 in the event it is desired to provide a decorative effect not inher-

ent in the material from which the parts are formed. For example, the cover member 51 may comprise a chromium plated metallic hood. The configuration of the parts makes it possible to slip the cover member in place where it will be retained without need for special fastening means, the configuration of the cover member being such that it will grip the lowermost end of the jacket, with the in-turned flange 52 seated on the skirt 11.

As should now be apparent, the shower head can be easily assembled in that the parts are readily engageable one with the other and snap-locked together by reason of the engagement of the various sets of locking fingers with the core part. Yet once assembled, the device is essentially tamper-proof in that there are no exposed means by which it may be disassembled. Due to its construction, there is little or no reason why the device need be disassembled. If, for some reason, it were desired to remove the deflector to clean around it, the entire shower head, including the ball fitting, may be removed from the supply pipe, whereupon a tool may be inserted through the ball fitting to release the bars 50 of the deflector which then may be removed. It may be replaced by simply aligning the gripping fingers 49 with the bar 25 and then moving them upwardly through the outlet orifice 35 until the bar is engaged.

It will be understood, of course, that modifications may be made in the invention without departing from its spirit and purpose. Certain of these modifications have already been pointed out, and others will undoubtedly occur to the skilled worker in the art upon reading this specification. Similarly, the utility of the device is not limited to use as a shower head. Rather, it will find utility in diverse other applications wherein an adjustable spray is required. Having, however, described the invention in an exemplary embodiment, what it is desired to secure and protect by Letters Patent is:

1. In a spray head having a body part including a passageway extending through said body part, means at one end of said body part for connecting said passageway to a water supply line, a nozzle part at the opposite end of said body part, an outlet orifice in said nozzle part in alignment with said passageway, means operatively connecting said nozzle part and said body part for rotation relative to each other, said means comprising a resilient locking finger secured to one of said parts, said locking finger having a barb-like projection thereon in locking engagement with an abutment means on the other of said parts, said abutment means comprising an inclined cam track operative upon relative rotation of said nozzle and body parts to effect axial movement of said parts toward and away from each other, depending upon the direction of their rotation, a button deflector overlying said outlet orifice on the discharge side thereof, and mounting means securing said button deflector to said body, whereby said nozzle part will be moved toward and away from said button deflector upon rotation of said parts relative to each other so as to thereby vary the flow of water through said outlet orifice.

2. The spray head claimed in claim 1 wherein said abutment means has an arcuate slot therein, and wherein said locking finger extends through said slot with the barbed portion thereof engaging said abutment means beyond a side edge of said slot.

3. In a spray head having a body part including a passageway extending through said body part, means at one end of said body part for connecting said passageway to a water supply line, a nozzle part at the opposite end of said body part, an outlet orifice in said nozzle part in alignment with said passageway, a spider-like member comprising a part of said body part, said spider-like member having one surface thereof facing said nozzle part and its opposite surface facing away from said nozzle part, an arcuate slot in said spider-like member, a first arcuate cam track lying beyond a side edge of said arcuate slot on the surface of said spider-like member facing away

from said nozzle part, a second arcuate cam track lying beyond a side edge of said arcuate slot on the surface of said spider-like member facing said nozzle part, a locking finger mounted on said nozzle part and extending through said arcuate slot, said locking finger having a barbed portion engaging said first cam track and an abutment thereon in engagement with second cam track, said cam tracks being equally but oppositely inclined relative to each other so that upon relative rotation of said nozzle and body parts said barbed portion will travel upwardly along said first cam track and said abutment will travel downwardly along said second cam track, and vice versa, depending upon the direction of rotation of said nozzle and body parts, a button deflector overlying said outlet orifice on the discharge side thereof, and mounting means securing said button deflector to said body, whereby said nozzle part will be moved toward and away from said button deflector upon rotation of said parts relative to each other so as to thereby vary the flow of water through said outlet orifice.

4. The spray head claimed in claim 3 wherein said body includes a swivel part, wherein the means mounting said body part to a water supply pipe comprises a ball coupling, and wherein said swivel part includes a socket forming part adapted to receive said ball coupling.

5. The spray head claimed in claim 4 wherein said swivel part includes a locking finger projecting downwardly therefrom, said body having a slot therein for receiving said last named locking finger, said last named locking finger having a barbed portion engageable beyond an edge of said last named slot.

6. In a shower head having a body part including a passageway extending through said body part, means at one end of said body part for connecting said passageway to a water supply line, a nozzle part at the opposite end of said body part, an outlet orifice in said nozzle part in alignment with said passageway, a cup-shaped spray chamber surrounding said outlet orifice and projecting outwardly on the discharge side thereof, means operatively connecting said nozzle part to said body part for relative rotation, said means comprising a pair of opposing locking fingers secured to one of said parts, said locking fingers each having a barb-like portion thereon in locking engagement with an abutment means on the other of said parts, said abutment means comprising cam means operative upon relative rotation of said nozzle and body parts to effect axial movement of the said parts toward and away from each other, depending upon the direction of their rotation, a deflector overlying said orifice on the discharge side thereof, said deflector having a stem member extending freely through said outlet orifice, and attachment means on said stem member securing it to said body, whereby said deflector will be mounted independently of said nozzle part so that upon axial movement of said nozzle part said outlet orifice will be moved toward and away from said deflector to thereby vary the flow of water through said outlet orifice.

7. The shower head claimed in claim 6 wherein a tubular neck portion surrounds said outlet orifice on the inlet side thereof, wherein said neck portion is slidably received in the passageway in said body, and wherein a gasket surrounds said neck portion and makes sealing contact with the wall surfaces of said passageway.

8. The shower head claimed in claim 7 wherein said abutment means has an opposing pair of arcuate slots therein, wherein said locking fingers project through said slots with their barb-like portions engaged beyond side edges of said slots, wherein said cam means comprises a pair of arcuate cam tracks lying beyond the side edges of said arcuate slots, with the barb portions of said locking fingers in engagement with said cam tracks, and wherein said body includes an annular recess facing said nozzle part, said annular recess defining a pair of arcuate cam tracks which are equally but oppositely inclined relative to said first named cam tracks, and wherein a pair of

opposed spacers project upwardly from said nozzle part and lie with their free ends in contact with said last named cam tracks.

9. The shower head claimed in claim 8 wherein said abutment means comprises a spider-like member forming a part of said body part, said spider-like member having one surface thereof facing said nozzle part and the opposite surface thereof facing away from said nozzle part, wherein said first named pair of cam tracks lie on the face of said spider-like member remote from said nozzle part, and wherein said annular recess is formed in the surface of said spider-like member facing said nozzle part.

10. The shower head claimed in claim 9 wherein a third pair of arcuate cam tracks lie beyond the side edges of said arcuate slots on the surface of said spider-like member facing said nozzle part, said third pair of arcuate cam tracks being equally but oppositely inclined relative to said first named pair of cam tracks, and wherein said locking fingers have abutments thereon contacting said third pair of arcuate cam tracks.

11. The shower head claimed in claim 10 wherein the means at one end of said body connecting said passageway to a water supply line comprises a detachable fitting, wherein said fitting includes an opposed pair of barbed locking fingers, and wherein said spider-like member has a second pair of opposed slots therein positioned to receive and engage said last named barbed fingers.

12. The shower head claimed in claim 11 wherein said fitting includes a socket member in communication with the passageway in said body, and wherein a ball coupling is mounted in said socket.

13. An adjustable shower head comprising a body having a swivel part and a core part, a nozzle part, and a deflector, said core part comprising a centrally disposed tubular member defining a water passageway, a jacket surrounding said tubular member and lying in spaced relation thereto, a spider-like member surrounding said tubular member and connecting it to said jacket, a pair of opposed slots defined in opposite sides of said spider-like member, and a pair of opposed elongated arcuate slots defined in the remaining sides of said spider-like member, said swivel part comprising a socket portion and a pair of depending locking fingers positioned to enter said first named pair of slots, said socket member being of a size to receive one end of said tubular member when said locking fingers are seated in said first named pair of slots, said nozzle part having a cup-shaped body terminating upwardly in a tubular neck portion surrounding a centrally disposed outlet orifice, a second pair of locking fingers projecting upwardly from opposite sides of said nozzle part in alignment with the said pair of arcuate slots in said core part, the tubular neck portion of said nozzle part being of a size to be received within the remaining end of said tubular member when said second pair of locking fingers are seated in said arcuate slots, said

5 second set of locking fingers mounting said nozzle part for rotation relative to said core part throughout the extent of said arcuate slots, cam means operatively engaging said second set of locking fingers, said cam means acting, upon 10 rotation of said nozzle part relative to said core part, to effect axial movement of said nozzle part relative to said core part, said deflector comprising a circular disk having a diameter greater than the diameter of the outlet orifice in said nozzle part, a pair of gripping fingers extending outwardly from one face of said circular disk and of a size to extend freely through said outlet orifice, and a bar mounted within said tubular member, said bar being positioned to be engaged by said gripping fingers, whereby 15 said deflector is secured to said core part so that said nozzle part, upon rotation thereof, will move relative to said deflector.

14. The shower head claimed in claim 13 wherein said spider-like member has an annular recess therein surrounding said tubular member and facing said nozzle part, 20 wherein said nozzle part includes an opposing pair of spacers projecting upwardly for engagement in said annular recess.

15. The shower head claimed in claim 14 wherein said cam means comprise arcuate cam tracks positioned to be 25 engaged by said second set of locking fingers, and wherein the bottom surface of the annular recess in said core part includes cam tracks adapted to be contacted by the ends of said spacers.

16. The shower head claimed in claim 15 wherein a ball coupling is press fitted in the socket of said swivel part to provide a water tight seal therebetween.

17. The shower head claimed in claim 16 wherein the tubular member of said core part is press fitted within the socket of said swivel part so as to provide a water tight 35 seal therebetween.

18. The shower head claimed in claim 17 wherein the tubular neck portion of said nozzle part has an annular shoulder mounting an O-ring, and wherein said tubular member has an enlarged portion defining a contacting 40 surface for said O-ring.

19. The shower head construction claimed in claim 18 wherein a decorative cover member is fitted over the jacket of said core part.
